BASKET

Paul W. Miessler, Cleveland, Ohio, assignor to
 The Hankins Container Company, Cleveland,
 Ohio, a corporation of Ohio

Application April 15, 1935, Serial No. 16,386

1 Claim. (Cl. 229—52)

The present invention relates to baskets and more particularly to baskets adapted for use in connection with the transportation of fruits and vegetables.

5 One object of the invention is to provide a sturdy and durable form of basket which can be conveniently fabricated from inexpensive materials without requiring any special form of tools or machinery.

10 Another object is to provide a basket formed from a blank of sheet material, such as corrugated paperboard, which can be quickly folded into basket form and can be readily assembled with a reinforcing strip which not only reinforces the basket walls but which at the same time serves to secure the blank into permanent basket form and to retain the basket handle in place.

15 Another object is to make possible the utilization of relatively thin corrugated board for fruit and vegetable baskets by so strengthening the narrow end walls that the assembly of a rim on to the side and end walls will cause the load imposed upon the side walls to be distributed in such a manner that, even with 20 the side walls of a single thickness, the tendency of the side walls to be deflected or distorted, even under relatively heavy loads due to stacking, will be reduced.

25 To these and other ends the invention resides in certain improvements and combinations of parts, all as will be hereinafter more fully described, the novel features being pointed out in the claim at the end of the specification.

30 In the drawing:

Figure 1 is a perspective view of a basket made in accordance with the present invention; and

Figure 2 is a plan view of the blank.

The basket, indicated as a whole at 1, comprises a blank 2 constituting a body portion, a 35 reinforcing rim 3 and a handle 4.

The blank or body portion 2, as shown in Fig. 2, is preferably formed of sheet material such as corrugated paperboard. In the present instance, the basket may very advantageously be formed from a relatively thin corrugated board sometimes designated as board formed with low 40 corrugations.

The blank 2 is scored and cut to form a bottom wall 5, side walls 6 and 7, and end walls 8 and 9. In the present instance it is preferred to form the narrow end walls of more than one thickness of board and for this purpose flaps 10, 10 and 11, 11 are formed respectively at 45 the ends of the elongated side walls 6 and 7. By

reference to Fig. 1 it will be noted that the flaps 10 and 11 at each end of the basket are folded inwardly so as to lie flat against the inner surfaces of the end walls 8 and 9.

The reinforcing strip 3 may advantageously be formed of a thin, relatively stiff strip of wood. This reinforcing strip is preferably formed of two separate pieces 3', 3'', each of such a length as to extend the entire length of one of the elongated, single-thickness side walls and over 10 a substantial portion of each end wall. The separate strips 3', 3'' are secured to the side and end walls as by means of staples 12, 12. In the present instance, the strips 3', 3'' extend 15 in overlapping relation with each other over a major portion of the end walls 8 and 9. It will be understood that the staples 12, 12 extend through the flaps 10, 10 and 11, 11 so as to secure these flaps directly to their adjacent end walls.

It will thus be noted that the end walls are 20 not only of double thickness but have a reinforcing strip thereon, a substantial portion of which is also double, accordingly, even using the relatively thin corrugated board, the end walls will be exceedingly stiff and rigid and capable 25 of bearing a relatively heavy load upon their upper edges which is the case when the baskets are piled one on top of the other in a freight car or truck.

The handle 4 is formed of flat material such 30 as a strip of wood, the ends of the handle being of such length as to terminate substantially at the lower edge of the reinforcing strip. The ends of the handle are secured in place between the reinforcing strip and the side wall as by means 35 of staples, 12, or other securing means. Thus, the handle will present no rough or uneven surfaces either on the inside or on the outside of the basket.

Due to the stiffness of the reinforcing strip the 40 load imposed upon the handle while the basket is being carried will not be limited merely to the fastening means which secures the handle in place but will be distributed on both sides of the handle along the side walls and an appreciable amount of the load imposed upon the handle will be transmitted to the end walls. The tendency of the handle to become detached from the basket is thus avoided.

Any load resting upon the side walls of the 50 basket will be distributed substantially evenly therealong due to the rigidity of the reinforcing strip and a certain amount of the load imposed upon an intermediate portion of the side walls will be transmitted to the end walls. It is there- 55

fore apparent that the basket of the present invention is admirably suited for shipment in box cars or trucks where it is desired to stack the baskets one upon the other to a considerable height.

By reason of the fact that loads imposed upon the edges of the side walls are transmitted to and borne to an appreciable extent by the double-thickness, rigid end walls, it will be seen that the body portion of the basket may be constructed from thinner paperboard than would otherwise be possible. Thus, the cost of the basket may be reduced without impairing its effectiveness.

By the utilization of the relatively stiff reinforcing strip 3 it is to be noted that it is not necessary to bring the ends of the handle down along the sides of the basket and the ends of the handle may therefore be terminated at substantially the lower edge of the strip 3.

As stated above, the weight on the handle is not only supported by the staple or other means for fastening the handle directly to the side wall but it is also supported by reason of the handle being attached to the reinforcing strip which latter, in turn, serves to help distribute the weight to the other portions of the side walls and the end walls.

Terminating the handle at about the lower edge of the reinforcing strip 3 also insures that the major portion of the side walls will be unobstructed, thus permitting the side walls to be effectively printed with any desired matter without the disadvantage of having the printing matter interfered with by unsightly, projecting handle ends. The arrangement by which the ends of the handle are secured between the side walls and the reinforcing strips not only provides for a smooth exterior but provides a smooth interior as well whereby there is no likelihood of the handle injuring the contents of the basket. This arrangement of handle also avoids other disadvantages inherent in baskets in which the handles extend along the faces of the side walls, namely, the handle ends when extended along the side walls tend to catch against each other when a basket is slid longitudinally closely adjacent to a similar basket.

From the foregoing it is apparent that the present invention provides an effective basket which can be quickly and easily formed and in

which relatively light and inexpensive materials may be employed. Due to the reinforcing rim and the manner of associating it with the double-thickness end walls, the tendency of the single-thickness side walls to collapse or become distorted under normal loads is eliminated; and, due to the effective construction of the basket, it is possible to employ thinner and weaker paper board than would otherwise be possible with other types of constructions.

While the present description sets forth a preferred embodiment of the invention, certain changes may be made in the construction without departing from the spirit of the invention, and it is therefore desired that the present embodiment is considered in all respects as illustrative and not restrictive, reference being had to the appended claim rather than to the foregoing description to indicate the scope of the invention.

I claim:

A basket formed from a blank of relatively thin corrugated board, said blank comprising a rectangular bottom wall, side walls on opposite sides of said bottom wall, end walls on each end of said bottom wall, end wall flaps on each end of said side walls, said end wall flaps each being of a length substantially equal to one-half the width of said end walls and lying against the inner surface of said end walls to form a double thickness end wall for said basket, a reinforcing rim of relatively stiff strip material secured in unbroken relation along the upper edge of each side wall, said strips overlapping each other to form double thickness strips across the end walls, means extending through said strips, end walls and end wall flaps to hold said basket in assembled relation, a U-shaped handle member of flat material, said handle member having its ends disposed between said strips and the side walls of said basket, means extending through each of said strips, handle member and side wall to hold said handle member in fixed relation to said basket, said strips serving to reinforce the entire upper edge surface of said basket whereby when a number of such baskets are stacked one upon another, a portion of the stresses imposed upon the edges of the side walls will be transmitted along said strips and carried by said double thickness end walls.

PAUL W. MIESSLER.
